STERILIZER

Alexander Louvier and Arthie Henry, Port Arthur, Tex., assignors of one-third to Sully Louvier, Port Arthur, Tex.

Application September 3, 1931, Serial No. 561,034

4 Claims. (Cl. 167—3)

This invention relates to sterilizing devices and more particularly to a sterilizing device wherein the articles placed therein may be easily and readily removed therefrom.

5 An object of this invention is to provide a sterilizer which is so constructed that a sterilizing liquid can be placed within the device and articles immersed in the liquid and at the same time articles supported above the liquid in a drying position.

10 A further object of this invention is to provide a sterilizer of this kind which is so constructed that it will comply with all of the requirements of the various boards of health in the locality in which the device is used and which at the same time embodies means for readily supporting the articles in the sterilizing fluid, the device including means whereby the articles may be readily withdrawn without inserting the hands or any implements in the sterilizing fluid.

15 The above and various other objects and advantages of this invention will in part be described in and in part be understood from the following detailed description of the present preferred embodiment, the same being illustrated in the accompanying drawings, wherein:—

20 Figure 1 is a longitudinal section taken substantially through the center of a device constructed according to the preferred embodiment 30 of this invention;

Figure 2 is a fragmentary sectional view taken on the line 2—2 of Figure 1;

Figure 3 is a transverse sectional view taken on the line 3—3 of Figure 1;

35 Figure 4 is a fragmentary perspective view of the front portion of the upper tray;

Figure 5 is a fragmentary perspective view of the rear portion of the upper tray, and

40 Figure 6 is a fragmentary perspective view of the rear portion of the lower tray.

Referring to the drawings wherein like numerals of reference designate corresponding parts throughout the several views, the numeral 10 designates generally a receptacle or liquid container which may be constructed of suitable material such as glass, porcelain, metal or the like.

45 The container 10 has an open top and a forwardly and upwardly inclined front wall 11. Preferably this container 10 is constructed of glass suitably treated so as to make it substantially unbreakable.

50 A lid 12 engages the upper end of the receptacle 10 and is provided at the sides thereof with depending flanges 13 which closely engage the side walls of the container 10 so that the cover or clo-

sure 12 snugly fits on the top of the receptacle 10. By providing these overlapping flanges 13, no dirt or dust particles can enter the interior of the receptacle 10 when the lid 12 is in closed position. The rear end of the lid 12 is provided with a U-shaped hinge member 14 which is integrally formed with the lid 12, this hinge member 14 being so constructed as to permit the swinging upward movement of the lid 12 at the rear wall of the container 10, while permitting the ready withdrawal of the lid 12 with the attachments hereinafter described, from the interior of the container 10.

55 Disposed within the container 10 there is an article supporting tray or member, generally designated as 15, which is constructed of perforate material in the form of wire mesh or the like, this tray 15 having a bottom 16, side walls 17, and a rear wall 18, which rear wall extends upwardly above the top of the side walls 17. In order to properly support the tray 15 within the interior of the container 10, we have provided a pair of depending looped strap members 19, which are secured to the inner face of the lid 12, these loop members 19 being secured in spaced relation to each other so as to properly support the tray 15 in a position above the bottom of the container 10 and inwardly of each side wall of the container. The front end of the tray 15 is preferably open so as to permit the ready positioning of articles or tools therein and to also permit the ready withdrawal of these tools when the lid 12 is raised upwardly by grasping the handle or tongue 20 which extends forwardly from the forward edge of the lid.

60 An upper tray generally designated as 21 is supported within the supporting straps 19 in a position where the bottom 22 thereof will be normally out of the liquid which is used for sterilizing the tools or articles in the lower tray 15 so that these tools may be withdrawn from the lower tray and placed into the upper tray for drying. The tray 21 has adjacent its forward or front edge depending flanges 23 which engage over the upper edge of the side walls 17 of the lower tray 15 and the side walls 24 of the upper tray 21 terminate inwardly of the rear end of the bottom 22 and are provided with a slit 25 so that the inner end of these side members 24 can overlap the upwardly extending side wall portions 26 of the lower tray side walls 17.

65 In the use of this device the desired sterilizing fluid may be placed within the tray or receptacle 10 to the desired depth and the articles in the form of tools or the like placed in the lower

110

tray 15. The lid 12 may then be placed over the open end of the receptacle 10 so as to suspend the tray 15 within the fluid and immerse the tools therein. When these tools have been properly sterilized they may be withdrawn by lifting up the forward end of the lid by grasping the tongue 20 and raising the forward end of the lid 12 with the U-shaped hinge member 14 as a fulcrum. The sterilized tools may be placed in the upper tray 21 which will be normally out of the fluid and the lid 12 again closed thereby preventing dust particles or germs from accumulating on the sterilized tools.

By providing the lower tray 15 with the upward-
ly extending rear wall 18 the lid 12 may be rocked upwardly without having the tools mounted in the lower tray 15 or in the upper tray 21 slide against the rear wall of the container 10. By constructing the trays 15 and 21 in superposed position any desired number of trays may be placed within the hangers or supporting members 19 depending only upon the depth of the container 10 and the depth of the hangers or supporting members 19. The draining member or tray 21 is slidably mounted on the upper edge of the tray 15, this being accomplished by extending the sides of the tray 21 adjacent the front end thereof, as at 23, outwardly and downwardly over the upper front edges of the lower tray 15 and the rear end of the draining tray 21 is provided with a slot 25 which receives the rear edge 26 of the lower tray 15 and the opposite edges of the draining tray 21 rest on top of the lower tray at these points. In this manner, the upper tray 21 can be readily removed when desired, either with or without the removal of the lower tray 15.

It is, of course, understood that various changes and modifications may be made in the details of construction and design of the above specifically described embodiment of this invention without departing from the spirit thereof, such changes and modifications being restricted only by the scope of the following claims.

Having thus described our invention what is claimed is:—

1. A sterilizing means comprising a perforated article receiving member having upstanding side walls, said side walls terminating adjacent one end in upward extensions and a draining tray 50 engaging the top of said member, said tray comprising a relatively flat member and upstanding

sides integral with the flat member, said tray having a rearwardly opening slot on each side at substantially the junction between the flat member and the sides to receive said extensions.

2. A sterilizing means comprising a perforated article receiving member having upstanding side walls, said side walls terminating adjacent one end in upward extensions, and a draining tray engaging the top of said member, said tray comprising a relatively flat member, upstanding sides integral with the flat member, said tray having a rearwardly opening slot on each side at substantially the junction between the flat member and the sides to receive said extensions and downwardly bent side portions integral with the flat member and disposed adjacent the front thereof to hold the tray against lateral movement on the top of the article receiving member.

3. A sterilizing means comprising a perforated article receiving member having upstanding side walls, said side walls terminating adjacent one end in upward extensions, and a draining tray engaging the top of the member, said tray comprising a relatively flat member, upstanding sides carried by the flat member, said sides terminating forwardly of the rear end of the flat member, said draining tray having rearwardly opening slots at the junction between the flat member and the sides to receive said extensions of said side walls of the article receiving member.

4. A sterilizing means comprising a receptacle, a lid for the receptacle, an article receiving member adapted to be removably disposed in the receptacle, means carried by the lid and engaging the member to removably support the member within the receptacle, said member including a lower sterilizing member having upwardly extending side and end walls, extensions integral with the side walls and an end wall, said extensions terminating rearwardly of the forward end of each side wall, and a draining means engaging the top of the lower sterilizing member, said draining means comprising a relatively flat member, upstanding sides carried by opposite edges of the member and downturned side portions carried by opposite edges of the member and adapted to engage over the sides of the lower sterilizing member to hold the draining member against lateral movement relative thereto.

ALEXANDER LOUVIER. 125
ARTHIE HENRY.
